[57] CLAIM

The ornamental design for a mounting plate for color standard tiles, as shown and described.

DESCRIPTION

FIG. 1 is a perspective view of the mounting plate for color standard tiles of my design;

FIG. 2 is a front view of the mounting plate of FIG. 1;

FIG. 3 is a back view of the mounting plate of FIG. 1;

FIG. 4 is a side view of the mounting plate of FIG. 1., the other side view being identical thereto; and,

FIG. 5 is an end view of the mounting plate of FIG. 1, the other end view being identical thereto.
